UNITED STATES PATENT OFFICE.

PIERREPONT B. NOYES, OF ONEIDA, NEW YORK, ASSIGNOR TO ONEIDA COMMUNITY LIMITED, OF ONEIDA, NEW YORK, A CORPORATION OF NEW YORK.

PROCESS OF POLISHING PLATED FLAT-WARE.

1,085,933.

Specification of Letters Patent.

Patented Feb. 3, 1914.

No Drawing.

Application filed July 3, 1913. Serial No. 777,275.

To all whom it may concern:

Be it known that I, PIERREPONT B. NOYES, a citizen of the United States, and resident of Oneida, Madison county, New York, have 5 made a certain new and useful Invention Relating to Processes of Polishing Plated Flat-Ware, of which the following is a specification.

This invention relates especially to processes for polishing plated flatware such as knives, forks, spoons and the like, which have been electroplated with silver for example, so as to produce the usual ornamental and protective coating. By strongly 10 pressing the electroplated flatware articles in planished dies the granular or frosted electroplated layer is pressed down or condensed or possibly flowed so as to produce a smooth, polished surface. 15 In carrying out this process the unplated spoons or other flatware articles, may be given their final form and provided with the desired ornamental design as by stamping in dies which are preferably highly 20 polished or planished where a smooth, polished surface is desired in the finished article. Then after such smoothing as seems necessary or desirable these articles are electroplated so as to give them a coating of 25 silver or other precious metal of the desired thickness which in the usual plating processes has a frosted or unpolished appearance. The plated articles may then be very 30 readily polished by pressing them strongly 35 in planished dies, preferably the same dies in which the unplated articles were finally pressed and this may be done in any suitable way as for instance in presses of various kinds used in this art, preferably those in 40 which heavy pressure and accurate alinement of the dies can be secured and in which the dies are forced slowly home upon the article, which minimizes wear of the dies and preserves the surface of their planished 45 portions and also seems to assist somewhat in securing the desired polishing of the article. By subjecting the electroplated articles to a slow, heavy pressure in the same finishing or design stamping dies used to 50 form the unplated articles in the first instance, a smooth, polished or planished surface can be readily secured throughout the desired extent of the articles at a single operation leaving little or no additional polishing to be done and greatly minimizing the 55

usual expensive hand buffing or other polishing methods necessary in finishing electroplated silverware in the customary manner.

This invention has been described in connection with illustrative machines, devices, 39 methods, processes of procedure, and orders of steps, to the details of which disclosure the invention is not of course to be limited, since what is claimed as new and what is desired to be secured by Letters Patent is set 45 forth in the appended claims.

I claim—

1. A process of polishing electroplated spoons and similar flatware articles which consists in gradually applying to the electroplated articles a heavy pressure in the same planished dies which were used for the final design stamping of the articles before they were electroplated and in simultaneously maintaining the alinement of said dies and 70 articles and in compressing and condensing the electroplated layer on said articles and causing it to conform to the contacting surface of the dies and thereby polishing the desired extent of the surface of the articles. 75

2. A process of polishing electroplated spoons and similar flatware articles which consists in applying to the electroplated articles a heavy pressure in the same planished dies which were used for the final design stamping of the articles before they were electroplated and in simultaneously maintaining the substantial alinement of said dies and articles and in thereby polishing the desired extent of the surface of the 80 articles. 85

3. A process of polishing electroplated spoons and similar flatware articles which consists in applying to the electroplated articles a heavy pressure in planished dies 95 and in simultaneously maintaining the substantial alinement of said dies and articles and in thereby polishing the desired extent of the surface of the articles.

4. A process of polishing plated spoons 100 and similar flatware articles which consists in gradually applying to the plated articles a heavy pressure in the same planished dies which were used for the final design stamping of the articles before they were plated and in simultaneously maintaining the alinement of said dies and articles and in compressing and condensing the plated layer on said articles and causing it to conform to the contacting surface of the dies and there- 105 110

by polishing the desired extent of the surface of the articles.

5. A process of polishing plated spoons and similar flatware articles which consists in applying to the plated articles a heavy pressure in the same planished dies which were used for the final design stamping of the articles before they were plated and in

simultaneously maintaining the alinement of said dies and articles and in thereby polishing the desired extent of the surface of the articles. 10
